UNITED STATES PATENT OFFICE

JAMES R. LAWLER, OF GLENCOE, ILLINOIS, ASSIGNOR TO DIRECT CONTROL VALVE COMPANY, OF CHICAGO, ILLINOIS, A CORPORATION OF DELAWARE

DESIGN FOR A RADIATOR VALVE

Application filed February 1, 1932. Serial No. 42,700. Term of patent 14 years.

To all whom it may concern:

Be it known that I, JAMES R. LAWLER, a citizen of the United States, residing at Glen-coe, Cook County, Illinois, have invented a new, original, and ornamental Design for a Radiator Valve, of which the following is a specification, reference being had to the accompanying drawings forming part thereof, showing my new design.

Fig. 1 is a detail perspective view of the valve.

Fig. 2 is a detail perspective view of the valve in a different position.

I claim:

The ornamental design for a radiator valve as shown.

JAMES R. LAWLER.
